UNITED STATES PATENT OFFICE.

CHARLES L. GOODRUM, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Specification of Letters Patent. Patented Jan. 15, 1918.

1,253,684.

Application filed December 30, 1916. Serial No. 139,802.

To all whom it may concern:

Be it known that I, CHARLES L. GOODRUM, a citizen of the United States, residing at New York, in the county of New York and State of New York, have invented certain new and useful Improvements in Telephone-Exchange Systems, of which the following is a full, clear, concise, and exact description.

10 This invention relates to machine switching telephone exchange systems with subscriber's control, and more particularly to systems containing a large number of offices. Experience has demonstrated that subscribers have difficulty in building up connections involving more than five digits.

15 The object of this invention is to enable a calling party to establish a connection with any other party in a large system without the necessity of remembering a large number of digits while operating his finger wheel.

20 In accordance with this invention, each calling line is provided with a number of manual devices, such as keys, for selecting and actuating one of a number of non-numerical switches at the office in which such line terminates to extend the line to one of the connecting circuits of the group leading to the desired group of called lines. This connecting circuit terminates in a first selector. This selector and succeeding selectors and a connector are then set by the calling party operating his finger wheel in the well-known manner. The calling party thus makes a preliminary selection of the first division, for example, the district, by a key, independently of the finger wheel, and then in operating his finger wheel to select 25 the office, thousands, hundreds, tens and units digits of the called line, need only remember five numbers or characters.

25 More specifically, each line terminates in a number of line switches each having access to a group of connecting circuits leading to a different line group, and each calling line is provided with a line relay for each line switch and with manual keys at the calling substation, for closing circuits to selectively operate said line relays to actuate the corresponding line switch. The calling party then operates his finger wheel to set the remaining numerical switches.

30 Referring to the drawing, which shows 55 only so much of a telephone exchange sys-

tem as is necessary for a comprehension of the invention, lines 1 and 2 terminate in brushes 3 and 4 of line switch A, and also in brushes 5 and 6 of line switch B at the central office. This line switch may be of the type shown in United States Patent No. 1,203,166. The calling line is also provided with a line relay 7 for controlling line switch A, and a line relay 8 for controlling line switch B, and with a common cut-off relay 9, which, when operated, removes the control of both of these line relays from the calling line. The group of line switches to which switch A belongs is controlled by a master switch 10, and the group of line switches to which switch B belongs, by a master switch 11. These master switches are shown and described in the patent to which reference has been made. The function of the master switch is to keep the brushes 3, 4, 12, 13 and 14 pointed toward an idle trunk. When a call comes in, the relay 56 operates and causes such brushes to engage the corresponding fixed terminals 15, 16, 17, 18, 19, thus seizing such trunk. The master switch 20 then causes the brushes of the remaining line switches to be moved into operative relation to the next idle trunk.

35 The invention will be more readily understood from a detailed description of the operation of the system. The party at substation C, desiring to make a call, depresses one of the keys 20, 21, depending upon the district in which the desired line is located. The depression of key 21, assuming the 40 called line to be in the district corresponding to this key, results in the closure of the following circuit: ground, key 21, conductors 2, 22, 23, inner armature and back contact of the cut-off relay 9, line relay 7 of line switch A to free pole of battery. Relay 7, in attracting its armature, closes the following circuit for magnet 56, from ground, armature and front contact of relay 7, left winding of magnet 56, conductor 27, left armature and back contact of locking magnet 28 of the master switch 10, to free pole of battery. Magnet 56, in attracting its armature 45 29, permits the brushes 3, 4, 12, 13 and 14 to engage the terminals 15, 16, 17, 18 and 19. The engagement of brushes 3 and 4 with terminals 15 and 16 energizes the stepping relay of the selector in which conductors 24, 50 25 and 26 terminate, which selector has access to groups of trunks leading to offices in 55

the selected district. This relay, in operating, causes a ground to be placed upon test wire 26, as fully shown and described in the above mentioned patent. The right winding of magnet 56 being now connected by brush 13 to said grounded conductor, the magnet maintains its armature attracted after the original energizing circuit through the left-hand winding is opened. This circuit is now opened by the deenergization of relay 7, following the energization of the cut-off relay 9 from free pole of battery, winding of relay 9, brush 12, to ground. The line relay 7 is constructed so as to be slow to release to prevent the opening of the circuit through the left winding of relay 56 before the circuit is closed through the right winding of said relay. The magnet 56 may also be made slow.

20 The engagement of brush 14 with terminal 19 grounds the contact 55 on the master switch contact bank corresponding to the connecting circuit just seized, and causes the energization of the starting relay 30 of the master switch 10, which, in operating, causes the master switch to advance the remaining plungers into operative relation with the next idle trunk. More in detail, the relay 30, in attracting its armature, closes the following circuit for the locking magnet 28: free pole of battery, magnet 28, armature and front contact of relay 30, right winding of supervisory relay 31 to ground. Magnet 28, in attracting its left armature, disconnects battery from the magnets 56 of the remaining line switches controlled by master switch 10, to prevent such line switches from being operated while the master switch 10 is moving. The attraction of the armature of relay 30 also causes the closure of a circuit for the trip magnet 32 if the arm 33 is in the position shown, which is its end position. In this event the following circuit is closed 45 due to the closure of contact 34: free pole of battery, magnet 32, contact 34, armature and front contact of relay 30, right winding of relay 31 to ground. The magnet 32, in attracting its armature, closes a circuit for the solenoid 35 of the master switch 10 to move the brushes of the remaining line switches into operative relation with trunk No. 1. Although the circuit of the trip magnet 32 is broken as the arm 33 in the first part of its movement opens contact 34, due to the armature of said magnet being locked by the catch 36, the circuit for such solenoid is maintained until such arm reaches its extreme position when it releases 50 the armature and breaks the solenoid circuit.

The calling line having thus been extended to an office selector, the calling party now removes his receiver and operates his finger wheel S to set the brushes 37, 38, 39 of the office selector into operative relation with

the group of trunks leading to the desired office in the district which has been selected. The switch then automatically finds an idle trunk 40, 41, 42 leading to such office. This trunk may be a two-wire trunk 43, 44 terminating in brushes 45, 46 at such office. The thousands and hundreds selector switches at such office (the latter not shown) may now be set by the calling subscriber to pick out a connector containing the wanted line. 70 The brushes 60, 61 of the connector are then set upon the multiples 62, 63 of the desired line. The selectors and trunk circuits are only diagrammatically shown, since they are well known in the art. They may be of the 75 type, for example, shown in Patent No. 1,203,166.

Assuming on the other hand that the called line is located in another district. Instead of depressing the key 21, the key 20 80 would be depressed by the calling party, resulting in the closure of the following circuit for line relay 8 of line switch B, ground, key 20, conductors 1, 47, 48, outer armature and back contact of relay 9, line relay 8, 90 free pole of battery. Relay 8, in attracting its armature, closes a circuit to operate magnet 49 of the line switch B, which, in attracting its armature 50, causes the seizure of the trunks 54, 51, 57, terminating in 95 brushes 52, 53, 58 of a selector having access to the offices in this district. From this point on the operation is the same as that already traced for the line switch A.

What is claimed is:

1. In a telephone exchange system, the combination with calling and called telephone lines, a plurality of automatic non-numerical switches for said calling line, connecting circuits leading from said switches in the direction of different called line groups, and manually operable devices associated with the calling line for selectively operating said switches to extend such calling line to a connecting circuit leading to the desired called line group. 100

2. In a telephone exchange system, the combination with calling and called telephone lines, a plurality of automatic non-numerical switches for said calling line, 105

connecting circuits leading from said switches in the direction of different called line groups, said circuits terminating in automatic numerical switches, manually operable devices associated with the calling 110 line for selectively operating said switches to extend such line to a connecting circuit leading to the desired called line group, other automatic numerical switches, and a sender associated with the calling line for 115 setting said numerical switches to interconnect the calling and called lines.

3. In a telephone exchange system, the combination with calling and called telephone lines, a plurality of line switches for 120

125

130

each calling line, a group of connecting circuits leading from each switch in the direction of different called line groups, and manually operable devices associated with the calling line for selectively operating its line switches to seize a trunk of the corresponding group.

4. In a telephone exchange system, the combination with calling and called telephone lines, a plurality of line switches for each calling line, a group of connecting circuits leading from each switch in the direction of different called line groups, said circuits terminating in automatic numerical switches, manually operable devices associated with the calling line for selectively operating its line switch to seize a trunk of the corresponding group, other automatic numerical switches, and a sender associated with the calling line for setting said numerical switches to interconnect the calling and called lines.

5. In a telephone exchange system, the combination with called telephone lines divided into groups, groups of connecting circuits each leading in the direction of a different line group, a group of non-numerical switches for each group of connecting circuits, a calling line, means controlled by the calling party for operating a non-numerical switch of any group to extend the calling line to one of the connecting circuits of such group, and means for extending the calling line over said connecting circuit in the direction of the called line.

6. In a telephone exchange system, the combination with called telephone lines divided into groups, groups of connecting circuits each leading in the direction of a different line group, a calling line, a non-numerical switch therefor for each group of connecting circuits, an electromagnetic responsive device for each switch for causing such switch to operate to extend the calling line to a connecting circuit of the group with which said switch is associated, and manual means associated with the calling line for selectively operating said electromagnetic responsive devices.

7. In a telephone exchange system, the combination with called telephone lines divided into groups, groups of connecting cir-

cuits each leading in the direction of a different line group, a calling line, a non-numerical switch therefor for each group of connecting circuits, an electromagnetic responsive device for each switch for causing such switch to operate to extend the calling line to a connecting circuit of the group with which said switch is associated, a manual key for each electromagnetic responsive device, and a circuit including one of said keys and the corresponding device and adapted when closed to operate the same to cause the corresponding switch to extend the calling line to one of the connecting circuits of the desired group.

8. In a telephone exchange system, the combination with called telephone lines divided into groups, groups of connecting circuits each leading in the direction of a different line group, a calling line, a non-numerical switch therefor for each group of connecting circuits to extend such line to said connecting circuits, a line relay associated with each calling line for each switch, means controlled by the calling party for selectively operating said line relays, and means controlled by a line relay when operated to cause the associated switch to extend the calling line to a connecting circuit of the desired group.

9. In a telephone exchange system, the combination with telephone lines divided into groups, called terminals therefor, groups of connecting circuits each leading in the direction of a different line group, a group of non-numerical switches for each group of connecting circuits for extending calling lines to said connecting circuits, a line relay associated with each calling line for each switch, means controlled by the calling party for selectively operating said line relays, means controlled by a line relay when operated to cause the associated switch to extend the calling line to a connecting circuit of the desired group, and a common cut-off relay operated when said line has been extended to disconnect all of said line relays from the calling line.

In witness whereof, I hereunto subscribe my name this 29th day of December, A. D., 1916.

CHARLES L. GOODRUM.
